UNITED STATES PATENT OFFICE.

GIUSEPPE VITULLI MONTARULLI, OF ROME, ITALY.

CONSTRUCTION OF SHIPS.

1,295,786.

Specification of Letters Patent.

Patented Feb. 25, 1919.

Application filed June 26, 1918. Serial No. 242,057.

To all whom it may concern:

Be it known that I, GIUSEPPE VITULLI MONTARULLI, a subject of the King of Italy, and residing at 29 Via Brescia, Rome,

5 Italy, have invented certain new and useful Improvements in the Construction of Ships, of which the following is a specification.

The invention relates to the construction 10 of ships and its object is a new system of hull construction adapted to provide a standard type of merchant vessel, this object being attained with aid of a structure wherein a central body member is combined with two lateral compartments which 15 form projections in the shape of saddles or hips on the central member and extend along the vessel for a certain length thereof.

According to the invention, the central 20 body member or inner hull is shaped so that it may be simple and cheap in construction and for this purpose it has preferably a tubular shape of circular cross-section, which also provides a greater organic 25 resistance of the structure without any increase of material.

The lateral compartments which form 30 containers for water ballast or for liquid or semiliquid cargoes, are intended to secure a great stability of the ship, as they increase the area of the water line surface and therefore the moment of inertia of this area, on which the metacentric height depends, and as these compartments are an integral 35 portion of the ship structure, they assist also in increasing its organic resistance or, with an equal resistance, in diminishing the hull weight, because they form a series of reinforcements in that part of

40 the vessel where in the ordinary construction the stringer plates and sheerstrakes are located. And as they are members of the girder, it may be said that their structure represents stringer plates and sheerstrakes which are more distant from the neutral fiber than the usual ones, so that they assist more largely in increasing the organic resistance.

In order that the features of the invention 50 may be more readily understood, the same will hereafter be described in one of its constructional forms with reference to the annexed drawings, in which—

55 Figures 1—1bis is a schematical longitudinal outside view of the ship,

Figs. 2—2bis is a plan view with the deck removed,

Figs. 3—3bis is a schematical longitudinal section,

Fig. 4 is a midship section and

Fig. 5 is a geometrical drawing of the shape of the bow and stern parts.

The ship is constructed with the aid of a plurality of Z bars 1 bent into rings and these rings form the frames of the ship 65 and their number varies in accordance with the length of the ship.

The rings 1 serve to build up the central part of the ship, while forward and aft they are replaced by frames which are 70 bounded by straight lines at the sides and by curves above and below and these curves gradually diminish in width until the frames are reduced to a straight line along the stern and bow stems. In Fig. 5, A 75 shows the molding of a frame of the central part of the ship and B, C, D, E and F the shape of the successive frames forward and aft.

The ship is quite symmetrical and both 80 its bow and stern ends are in the shape of a flute-beak, i. e. they form a conical surface whose vertex is a straight line (bow and stern stem) and not a point.

The circular frames 1 are interconnected 85 by stringers 2 (rectilinear generatrices) made of Z bars. On the Z bars 1 and 2 are riveted plates 3 which are bent so as to have circular cross section and at the bow and stern ends are partly rectilinear, 90 so as to fit snugly on the frame work, and they surround the whole hull and leave openings only for the hatchways 4 in the top part.

The hull member will be divided by bulkheads 5 into intercommunicating watertight compartments so as to obtain the several holds, the machine and boiler rooms, the coal bunkers and the bow and stern tanks, and it will further be provided with 100 water intakes, screw shaft and tunnel, motor stand and rudder.

All the above described operations to assemble the parts which form the hull may be carried out on a sea-shore and when 105 they have been completed, the hull is ready to be launched, for which purpose all the openings are closed and the hull can be made to roll on beams down the shore into the water. The hull will here be immersed 110

to about one third of its diameter by suitably ballasting it, which will also prevent dangerous movements during the operations now to be carried out on the hull.

5 The more important of these successive operations is to apply the lateral compartments which, under full load, will generally be immersed for more than ten feet and they will extend along a certain length of
10 the hull, so as to protect it efficiently against torpedoes and mines and to localize damages produced thereby, in combination with the transverse subdivision of the hull.

The lateral compartments are constructed
15 by aid of frames 6 of Z bars and of stringers 10 and are covered with plates 11. The outer halves of the frames which form the hipped or lateral compartments, are substantially in the shape of a semi-circle, while the inner 20 halves engage the main body of the hull and are concave so as to follow its outline. The lateral compartments form separate tanks and are also subdivided into water-tight compartments. They will be provided with
25 tightly closed hatches 7 and they may be used for water ballast or for the transportation of liquid and semi-liquid goods and the whole ship may thus carry simultaneously or alternately solid and liquid cargoes in the
30 hull member and the lateral compartments respectively.

It is evident that in view of their special curvature all the principal parts of the frame work and of the plating are equal to, 35 and interchangeable between, each other, so as to permit to standardize not only the type of ship as a whole but also its various members singularly, and these members may not only be constructed in series, but the plates
40 may also be cast or drawn integrally with the stringers, whereby the riveting work will be greatly diminished, and the central part or hull member may be built up of tubular segments without the use of frames or
45 stringers.

When the lateral compartments have been arranged on the inner hull member, the ship will be further equipped in any usual or desired way.

50 What I claim is:

1. A ship having curved transverse frames

throughout the waist of the ship, the outboard portions of said frames having straight sections the length of which progressively increase toward the stem and stern thereby giving the ends of the ship the shape of a flute beak.

2. A ship having a plurality of transverse frames, the frames throughout the waist of the ship being curved and the frames upon the opposite ends of said waist having their outboard portions straight the length of which progressively increases toward the stem and stern thereby giving the ends of the ship the shape of a flute beak, and plates
65 secured to the transverse frames and conforming to the shape thereof.

3. A ship having a plurality of transverse frames, the frames throughout the waist of the ship being circular and the frames upon
70 the opposite ends of said waist having their outboard portions straight the length of which progressively increases toward the stem and stern thereby giving the ends of the ship the shape of a flute beak, plates secured to the transverse frames and conforming to the shape thereof, and lateral compartments arranged upon the opposite sides
75 of the waist of the ship and secured thereto.

4. A ship having a plurality of transverse frames, the frames throughout the waist of the ship being circular and the frames upon the opposite ends of said waist having their outboard portions straight the length of which progressively increases toward the
80 stem and stern thereby giving the ends of the ship the shape of a flute beak, plates secured to the transverse frames and conforming to the shape thereof, and lateral compartments arranged upon the opposite sides
85 of the waist of the ship and secured thereto, said lateral compartments having outer convex sides and inner concave sides conforming to the curvature of said waist.

In testimony whereof I have signed my name in the presence of two subscribing witnesses the 25th day of May 1918.

GIUSEPPE VITULLI MONTARULLI.
